UNITED STATES PATENT OFFICE.

PAUL F. SMITH AND JAMES A. LUKE, OF SALT LAKE CITY, UTAH.

DRY-CLEANING SYSTEM.

1,385,724.

Specification of Letters Patent. Patented July 26, 1921.

Application filed June 12, 1920. Serial No. 388,497.

To all whom it may concern:

Be it known that we, PAUL F. SMITH and JAMES A. LUKE, citizens of the United States, residing at Salt Lake City, in the

5 county of Salt Lake and State of Utah, have invented certain new and useful Improvements in Dry-Cleaning Systems, used in dry-cleaning clothes-washing machines, and we do hereby declare the following to be 10 a full, clear, and exact description of the invention.

In the usual dry process of cleaning clothes and other fabrics by the use of washing machines, the customary mode of procedure is to place in the washer about five 15 pounds of dry cotton rags to absorb the moisture in the gasoline, and these rags are agitated about five minutes in the detergent to prepare it for the clothes washing. These 20 rags are then removed from the washer and placed in an extractor for the purpose of extracting gasoline and water therefrom. The water and gasoline are run off in a bucket and allowed to settle, the gasoline 25 rising to the top and is recovered, the water being dispensed with, and the rags are then hung out to dry.

The next customary mode of procedure is to place the clothing in the washer and 30 furnish gasoline, naphtha, or other liquid detergent or cleansing fluid to the interior of the washer, together with additional cleansing material, as soap, agitate the contents for say twenty minutes, and when the 35 clothing has been sufficiently agitated and cleansed, the cleansing fluid is drained off in a settling tank, and a new supply of gasoline, or distilled gasoline or cleansing fluid, is pumped into the washer for the purpose 40 of rinsing the fabrics or clothing that have previously been washed, requiring additional time and agitation. The detergent is then returned to the settling tank, and the fabrics and clothing are removed from the washing 45 machine and placed in a centrifugal extractor for the purpose of extracting the cleansing fluid from the fabrics, which fluid is drained into one of the above mentioned settling tanks.

50 The fabrics or clothing are now dried, either by placing them in a drying room and then subjecting them to a dust wheel, or by using a drying tumbler in the presence of hot air forced therein. In either event 55 the clothing is subjected to more wear, and the breaking of buttons, and other objec-

tionable consequences, namely loss of the nap, rendering the clothes threadbare and consequently more shiny when subsequently pressed.

60 The cleansing fluid or detergent used in the above process quickly becomes dirt-laden and must be permitted to settle, which takes at least twenty four hours of time, and is unsatisfactory, or the liquid must be distilled, 65 which entails a loss of at least 25% of the gasclene, or naphtha, and the entire loss of all soap values therein.

The object of our invention is to produce a 70 process, and means, for carrying out the process, whereby a continuous circulation of the liquid detergent is maintained between the source of supply of the detergent and the washing machine, and the liquid detergent is cleansed and purified immediately 75 after use, without necessity for settling or distilling, and then returned as a clarified liquid directly to the washing machine, consequently eliminating the necessity for rinsing of the clothing.

80 In carrying out our invention we utilize in connection with the washing machine or machines, a tank for receiving the soiled detergent from the washing machines and by a pump convey the soiled gasoline from this 85 tank to a filter, which is of the centrifugal extractor type, and from thence return the purified gasoline to the washing machine or machines.

The filter or extractor is also constructed 90 of novel form and is made up of combinations and arrangements of parts whereby the previous riffles, or walls thereof, are rendered efficient in gathering the dirt, grease, and solid matter previously extracted from the 95 clothing or fabric in the washers, and in eliminating and separating the dirt and grease from the detergent or cleansing fluid, as the fluid passes through the riffles forming the walls of the filter.

100 In the accompanying drawings we have illustrated one complete example of the physical embodiment of our invention, in which the several parts are combined and arranged according to the best mode we 105 have thus far devised for the practical application of the principles of our invention, and which exemplification has been found satisfactory, efficient, and economical in producing the results to be accomplished as the 110 objects of our invention.

It will be understood however, that the

embodiment illustrated is a mere exemplification of one form of the invention, and that colorable changes may be made in the invention within the scope of the appended 5 claims, without departing from the spirit of the invention.

Figure 1 is a diagrammatic view showing the physical embodiment of our invention as used in actual practice, and illustrating the 10 device employed in the circulation and filtering system, by means of which the clarified detergent is continuously supplied to the washing machine or machines.

Fig. 2 is an enlarged, vertical sectional 15 view of the centrifugal extractor or detergent filter.

Fig. 3 is a sectional view, partly in perspective, showing the relation of the successive riffles forming the pervious walls of 20 the basket of the filter.

Fig. 4 is a plan view of an additional filter riffle, with the covered riffle bars arranged in vertical and oblique positions.

Fig. 5 is a sectional view of a riffle and 25 riffle bar, showing the latter covered with fabric, as canvas.

In the preferred form of the invention as illustrated in the drawings, especially Fig. 1, the washing machine is of any well known 30 type, fashioned in suitable form and of proper size, and supported above the floor or ground.

The dirt laden detergent or cleansing fluid, such as gasolene, naphtha, or the like, 35 after performing its function in the washing machine, passes from the washer 1 through one or more discharge pipes 2 connected to the bottom of the washer and extending vertically to the receiving tank 3, 40 preferably located beneath the surface of the floor or ground, and formed with a conical bottom 4.

The discharge pipe for the gasolene extends to the receiving tank for the admission 45 of dirt laden cleansing fluid, and a suction pipe 5, which terminates near the bottom of the receiving tank is connected to the main suction pipe 6 for drawing the gasolene therefrom.

50 A pump 7 is interposed in the pipe 6, which forces the dirt laden gasolene through the pipe 6' to a filter 8, which is in the nature of a centrifugal extractor or filter, and located above the washing machine in order 55 that the clarified or purified gasolene may flow by gravity from the filter to the washing machine.

Fresh gasolene may be drawn from the 60 tank 3' provided with the usual conical bottom 4', and also located beneath the ground line. A suction pipe 5' from the fresh gasolene tank 3' is connected to the filter pipe 6' above the pump 7 and also below the pump by branch pipe 5''. By manipulating the several valves V, V' and V''

in the pipes, the passage of fresh gasolene, and soil-laden gasolene, may be controlled, and when fresh gasolene is used the valve V'' is closed. The fresh gasolene then flows through pipe 6'' to pipe 9.

In Fig. 2 it will be seen that the body 8 of the filter is preferably made of sheet metal with a cast bottom 10, and a similar top ring 11, above which is provided a hood 11' to prevent splash of liquid, and to retain 70 the vapor within the device. The driving shaft 12 is journaled at 13 in the bottom of the filter, and this shaft projects upwardly a suitable distance to receive the basket indicated as a whole by the numeral 14, the 75 imperforate bottom 15 of the basket being secured on the head of the shaft to revolve therewith. The basket is designed to receive the liquid detergent to be cleansed through the perforated nozzle or pipe 15' 80 and the basket is spaced within the filter 8 to provide an annular space or chamber 16 around the basket and within the filter.

The basket is formed with walls that are 85 pervious to the liquid detergent, as gasolene, and these walls are made up of a plurality of riffles, of canvas layers, and of other 90 materials of different mesh, that will permit passage therethrough of the liquid detergent.

95 As an example of the construction of the basket walls of the filter, attention is particularly called to Fig. 3, wherein the inner shell 17 is of canvas, forming the inner surface of the basket, and this surface is smooth, 100 and soft, to prevent friction and possible ignition, from metallic or other hard materials.

105 A canvas riffle 18 is located outside the shield 17, this riffle, as is the case with the shield and the other riffles, being a circular, flexible, pervious band, which, when made 110 up of fabrics has a selvage edge to render it more durable. Upon the inner vertical surface of the riffle 18 are provided riffle bars 19 and 20, preferably of wood and spaced apart at regular intervals around the inner surface of the riffle, and as seen in the drawings, these bars 19 20 are preferably of alternate sizes, but made up of uniform sets. 115 The bars are uncovered, the wood strips being stitched in suitable manner to the flexible or canvas riffle, and readily detachable therefrom when required.

120 Concentric with and outside the riffle 18 a plane riffle 21, similar to the shield 17, is provided, and this riffle is succeeded by the concentric canvas riffle 22 which is provided with vertically arranged riffle bars 23 of wood strips, uncovered, and stitched 125 to the canvas riffle 22.

130 Outside the canvas riffle a reticulated annular screen 24, of wire mesh, is located, being covered with the inner and outer layers 25 and 26 respectively, of canvas, and a

thickness of felt, as 27, is located between this metal screen and the perforated thin metallic plate 28, also inclosed by the layers of canvas 29 and 30, similar to the reticulated screen 24.

The exterior canvas riffle 31 surrounding these successive partitions is provided with a series of intermediate, vertically arranged riffle bars 32 at its inner side, and also two rows of angularly disposed riffle bars 33 and 34, which are preferably canvas covered, as at 35.

These successive pervious, annular partitions of different permeability are all adapted to permit passage of liquid detergent therethrough, and they are built up and braced, and supported from the bottom or other portion of the basket in such manner as to provide stable wall-structures for the revolving basket, through which the detergent is forced by centrifugal action.

The several riffles and metallic screens form a wall of sufficient strength to resist the pressure due to the action of the revolving basket, and yet the riffles or layers are so related as to permit the detergent to permeate and pass therethrough. The riffle bars, as the riffles revolve, perform the function of gathering and retaining the major portion of the coarse dirt and sediment as it has been softened by the detergent and extracted from the clothing in the washing machine. The alternately arranged large and smaller riffle bars on the riffle 18 are utilized to gather deposits of coarse and finer sediment, and the smaller riffle bars on the outer riffles 22 and 31 are designed to gather the very fine sediment, and these and other riffles are taken out from time to time and cleaned of their deposits, as required.

The composition of the pervious walls of the basket may be varied, and canvas riffles with plaits in them may be used as riffle bars in conjunction with the riffle bars described as being made of wood. Canvas of fine or coarse texture may be used and the mesh of the metallic screens may also be varied in use, and similar changes are contemplated in the weight or thickness of the felt, and the number of riffles may be varied, in order

to adapt the pervious basket walls for various conditions.

We have found that at least one half of the cleansing properties of the soap solution remains in the filtered gasolene as it is returned to the washing machine from the gasolene filter, thus saving considerable in expense of maintaining the soapy condition of the detergent, and at the same time all atmospheric moisture is relieved from the gasolene. In view of the fact that the detergent or gasolene, used herein, does not require heating, no loss of gasolene is sustained by evaporation due to heating. By the utilization of our process and cleansing means, the clothing is cleaned in the washer, and as a result of this treatment, a fine and pleasing feeling and appearance of the cleaned and dried clothing is attained.

What we claim is—

1. A closed dry cleaning system adapted to continuously circulate the cleansing liquid comprising in combination a dry cleaning machine, a receiving tank and a drain pipe from said machine to the tank for the dirt laden cleansing fluid, a pipe line from the tank and a pump in said line, a filtering device connected to the pump, and a supply pipe from said filter to the dry cleaning machine.

2. A closed dry cleaning system adapted to continuously circulate the cleansing liquid comprising in combination a dry cleaning machine, a receiving tank and a drain pipe from said machine to the tank for the dirt laden cleansing liquid, a pipe line from the tank and a pump in said line, a supply tank connected to the pump, a filtering device connected to the pump, and a supply pipe from said filter to the dry cleaning machine.

3. A dry cleaning process which consists in placing soiled clothes in a dry cleaning machine, supplying cleansing liquid thereto, continuously withdrawing dirt-laden cleansing liquid from said machine, filtering it and continuously returning to the dry cleaning machine.
